UNITED STATES PATENT OFFICE.

ROBERT S. HAMMOND, OF CHICAGO, ILLINOIS, ASSIGNOR TO AMERICAN STEEL
FOUNDRIES, OF CHICAGO, ILLINOIS, A CORPORATION OF NEW JERSEY.

CARRIER-IRON.

1,287,679.

Specification of Letters Patent. Patented Dec. 17, 1918.

Application filed June 11, 1917. Serial No. 173,988.

To all whom it may concern:

Be it known that I, ROBERT S. HAMMOND, a citizen of the United States, and a resident of Chicago, in the county of Cook and 5 State of Illinois, have invented certain new and useful Improvements in Carrier-Irons, of which the following is a specification.

My present invention relates to improvements in carriers for various purposes and 10 more particularly for couplers for railroad rolling stock.

The principal objects of my present invention are to provide a unitary carrier, to provide an improved form of carrier which 15 may be secured to the striking casting or between the draft sills without the use of any additional devices such as pins, cotters, nuts, bolts or the like and without the use of tools of any kind; to provide improved 20 means for preventing the disengagement of the carrier with the striking casting, to provide a carrier adapted for use with striking castings for new cars, or economy draft arms or other draft arms for old cars, and generally to improve, simplify and cheapen the 25 construction of carriers and striking castings and the parts associated therewith.

In attaining these and other objects and advantages to be hereinafter set forth, I 30 have provided a construction two embodiments of which are illustrated in the accompanying drawings, in which—

Figure 1 is a front view, parts being in section, of the carrier and the parts of the 35 striking casting engaging therewith;

Fig. 2 is a section on the line 2—2 of Fig. 1.

Fig. 3 is a section on the line 3—3 of Fig. 1;

Fig. 4 is similar to Fig. 3 and shows the carrier in position to be disengaged from the striking casting;

Fig. 5 is a side view of the construction shown in Fig. 1, taken from the left hand 45 side; and

Fig. 6 is a plan view of a modified form of construction.

Considering first the form of construction shown in Figs. 1 to 5, the carrier consists 50 of a single casting 10, having its ends carried in apertures 11 and 12 of the side portions 13 and 14 of the striking casting.

The carrier and these apertures in the striking casting are so constructed relatively 55 to each other that when the carrier is in

the position shown in Fig. 1 it cannot move longitudinally with respect to the striking casting, but when lifted it can be moved into or out of engagement with the striking casting. The dimensions of the ends of the 60 carrier and the aperture are such that the carrier may be placed in position and removed within the limit permitted by the clearance of the coupler between it and the top of the striking casting when the coupler 65 is in its normal position.

It will be seen that the carrier comprises four projecting portions which engage the walls of the striking casting on one side or other of the apertures 11 and 12. The projecting portions are respectively 15, 16, 17 and 18. It will be seen on inspection of Figs. 2 and 5 that the projection 15 prevents movement of the carrier toward the left and the carrier as will be described later 70 is disengaged from the striking casting by movement to the right. The projecting portions 16 and 17 grip the part 21 of the striking casting therebetween. The part 18 engages the part 19 of the striking casting. 80

By lifting the left-hand side of the carrier and simultaneously moving it to the left as shown in Fig. 3, the right hand portion 20 of the carrier may be moved clear of the projection 21 so that the part 17 may be 85 lifted into the position shown in Fig. 4 in which position the projections 18 and 16 are brought into register with the lateral extensions 22 and 23 of the aperture 12. In this position the carrier may be withdrawn. 90 Therefore, to disconnect the carrier member from its normal locked position, as shown in full lines in Fig. 3, the left-hand side of the carrier member, as viewed in said figure, is tilted upwardly about a longitudinal axis 95 thereof, the carrier member then moved bodily to the left, the right-hand side of the carrier member then tilted upwardly about a longitudinal axis thereof, and then moved bodily longitudinally far enough to disconnect the left-hand end of the carrier member, as viewed in Fig. 1 from its seat, whereupon

that end of the carrier member may be lowered and the other end withdrawn by a reverse bodily movement to the left. Due 105 to the necessity of these various releasing movements of the carrier member, it is apparent that it cannot be accidentally disengaged as a result of jolts incident to service conditions. The part 20 of the carrier is 110

beveled along its upper edge and the part 21 of the striking casting extends over this beveled part and thereby prevents the carrier jumping up and down under vibration 5 and shocks and also makes accidental displacement almost impossible. The part 20 is beveled to accommodate the part 21 instead of arranging the part 21 to lie wholly above the surface of the carrier to enable the carrier to be removed within the clearance allowed between the top of the coupler and the striking casting. It will be observed that the aperture 11 is made of considerably greater height than the thickness of the carrier 10 10 so as to allow the carrier to be tilted in one direction as shown in Fig. 3 and then in the opposite direction as shown in Fig. 4 in order to bring the carrier into disengaging position.

20 The method of inserting the carrier into the striking casting is, of course, the exact reverse of the method of removing it.

In order to facilitate the insertion or removal of the carrier the recesses 24 are arranged in one end of the carrier adapted to act as hand holds for gripping the end of the carrier. The central portion of the carrier is raised to substantially the height that the upper surface of a centering device 25 would have were one used. This construction is adopted with a view to enabling the striking casting to be equipped either with a carrier or with a combined carrier and centering device. It will be understood 30 however that the central portion may be not raised, but may lie in the same plane as the end portions.

The raising of the central portion of the carrier produces shoulders 25 which prevent 40 (with the size of aperture shown) the carrier being withdrawn as a whole through the aperture 12. Consequently after the carrier has been moved toward the right sufficiently far to bring its left hand end out of engagement with the aperture 11 that end of the carrier is dropped and then the carrier as a whole is moved downwardly toward the left in order to bring the other end of the carrier out of engagement with the striking 45 casting. It will be observed that the lower edge of the part 18 of the striking casting is beveled at 26 to facilitate passage of the carrier thereby. Similarly, the upper edge 27 of the aperture 12 is beveled for the same purpose.

It will be observed that the ends of the carrier are shaped differently so that the carrier cannot be placed in position wrong end to. In the form of construction illustrated, one end is made wider than the other so that the ends cannot be reversed relatively to the striking casting.

In the modification shown in Fig. 6 the carrier has no raised center portion and can 60 therefore be withdrawn through one aper-

ture as can also be done with the device shown in Fig. 1 when it is made flat, that is, without the raised portion. The projecting parts 28, 29 and 30 being brought out of engagement with the walls of the aperture 31 70 in exactly similar manner to that described in connection with Figs. 3 and 4.

Having thus described my invention and illustrated its use, what I claim as new and desire to secure by Letters Patent is: 75

1. A device of the character described comprising in combination a supporting member, a carrier member, said supporting member having apertures adapted to receive the ends of said carrier member, and projecting portions on said carrier member adapted to normally engage opposite faces of said supporting member and thereby prevent accidental longitudinal movement of said carrier member relatively to said supporting member and being disengageable from said faces by a tilting movement of the carrier member about a longitudinal axis thereof and being removable from the supporting member by a longitudinal movement. 80 85

2. A device of the character described comprising in combination a striking member, a carrier member, said striking member having apertures adapted to receive the ends 90 of said carrier member, and projecting portions on said carrier member adapted to engage opposite faces of said striking member, one of said apertures being of greater height than the thickness of said carrier member 95 and having a lateral extension adjacent its upper part adapted to allow of the passage of said projecting portions when the carrier member is lifted.

3. A device of the character described 100 comprising in combination a striking member, a carrier member, said striking member having apertures adapted to receive the ends of said carrier member, and projecting portions on said carrier member adapted to 105 engage opposite faces of said striking member, one of said apertures being of greater height than the thickness of said carrier and having on one side a lateral extension adjacent its upper part adapted to allow of the 110 passage of said projecting portions when the carrier member is lifted, and on the other side an inwardly extending projection adapted to check such lifting movement and thereby prevent accidental disengagement of 115 said carrier and striking members.

4. A device of the character described comprising in combination a supporting member, a carrier member, said supporting member having apertures adapted to receive 120 the ends of said carrier member and interlocking portions on said carrier and supporting member disengageable by not less than 125 two separate tilting movements of the carrier member about longitudinal axes there- 130

of, whereby accidental longitudinal movement of said carrier member is prevented.

5. A device of the character described comprising in combination a supporting member, a carrier member, said supporting member having apertures adapted to receive the ends of said carrier member and interlocking portions on said carrier and supporting member disengageable by not less than three separate movements, two of said movements of the carrier member being about longitudinal axes thereof, whereby accidental longitudinal movement of said carrier member is prevented.

6. A device of the character described, 15 comprising in combination, a supporting member and a carrier member, said supporting member and carrier member having interlocking portions disengageable by not less than two separate tilting movements of the 20 carrier member about longitudinal axes thereof, whereby accidental longitudinal movement of said carrier member is prevented.

Signed at Chicago, Illinois, this 22nd day 25 of May, 1917.

ROBERT S. HAMMOND.
